FULL AUTOMATIC COP WINDING MACHINE

Walter Schweiter, Horgen, Switzerland

Application March 21, 1939, Serial No. 263,275
In Germany June 23, 1938

22 Claims. (Cl. 242—41)

This invention relates to cop winding machines of the type in which the full bobbins are replaced by empty bobbins entirely automatically at the end of the winding operation.

More particularly it relates to such a machine in which for each winding spindle there is a complete set of automatic actuating members having their own power shaft and preferably contained in a closed box or casing, individual to each spindle, serving as the machine frame therefor. The invention consists, among other things, of improved means for clamping the cops in the winding position and rotating and stopping them in such position and releasing them, all with the least possible delay and so as to increase thereby the productive rate of the machine as hereinbelow pointed out in connection with the exemplification shown in the accompanying drawings wherein

Fig. 1 shows the gear box in longitudinal section along the main driving shaft,

Fig. 2 is a top plan view of Fig. 1,

Fig. 3 is a longitudinal section taken along the winding spindle,

Fig. 4 shows partly in elevation and partly in section a safety device against too high resistances,

Fig. 5 shows partly in side elevation and partly in longitudinal section a gear box with starting device and individual drive.

Fig. 6 shows a plan with power shaft removed to show the underlying mechanism.

A driving shaft 1, journaled in bearings 3 and 4 in a gear box 2 so that it can rotate and at the same time be axially shifted a few millimetres, carries on its outer end a friction disc 5 driven by a friction wheel 6 keyed on a driving shaft 7 common for several spindles. The frictional pressure necessary for effecting the drive is produced by a spring 8 which bears at one end against a collar 9 on shaft 1 and at its other end against a race ring 10 of a thrust ball bearing 11 which in turn bears against a grooved ring 12. A clutch fork 13 engages in the groove 12a of the grooved ring 12 and is keyed on an axle 15 rigidly connected to an engagement lever 14. A pull spring 17 is attached at one end to the rear end 16 of the engagement lever 14 (Fig. 5) and at its other end to a pin 33 fixed in the box 2, and tends to pull the clutch lever into its disengaged position.

In the disengaged position the grooved ring 12 bears against the worm 18 keyed on the driving shaft 1 and, through the pull exerted by the spring 17, presses forward the shaft 1 with the

result that the friction disc 5 is no longer in contact with the driving wheel 6; consequently the apparatus comes to a standstill.

If the engagement lever 14 is pressed downwards by hand, the clutch fork 13 pushes the grooved ring 12 towards the rear so that the friction disc 5 is pressed against the driving wheel 6 by the spring 8 now becoming operative and starts up the shaft 1 and consequently the whole gear.

The engagement lever 14 is held in its engaged position by an adjustable stop 19 fixed on it, which stop bears against a crescent-shaped projection 20 on a strap 21 oscillatably mounted in the box 2.

A resilient thread guide 22 is fixed at one end on the strap 21 and carries at its other end a guide roller 23 over which the thread 24 runs. Owing to the pull exerted by the thread 24 the strap 21 is held in the position illustrated in Figs. 1 and 5. If the thread breaks the strap 21 swings downward under the action of gravity so that by turning the crescent-shaped projection 20, the stop 19 is liberated and the engagement lever 14 pulled into its disengaged position by the spring 17.

A compound worm and spur gear, 26—27, is mounted rotatably on the shaft 1 and is axially shiftable thereon by cam connections presently described. It is driven by this shaft through the intermediary of a multiple disc clutch 25, which comprises, in known manner, alternate disc members keyed at 31 to the driving shaft 1 and intervening disc members keyed to finger extensions 30 on the worm 26. The discs are pressed together to produce the necessary friction between the compound gear and the end of the worm 18 which latter is fast to the driving shaft 1. The worm 26, through the intermediary of a worm wheel 28 on a suitable countershaft, drives the drum cam 29 which imparts the oscillating movement to the thread guide (not shown on the drawings) through which the thread is guided while it is being wound on the cop. The spur gear 27 drives a spur gear 34 fast on the spindle 34a of the bobbin-driving head 35, which spindle is mounted in a bearing sleeve 36 axially shiftable in the box 2.

The worm 18 drives a spur gear 40 through the intermediary of a compound gear 37, 38, rotatably mounted on a rock shaft 39 which is journaled in the box 2. This spur gear 40 is free on another counter-shaft, herein called the control shaft, 41, and carries a plurality of studs or catch-pins 42. A disc 43 (Fig. 2) is keyed on the

control shaft 41, and carries a dog 45 pivoted thereon at 44 and pressed inwards by a spring 46. The dog is adapted to make connection with one of the pins 42 in order that the gear 40 may drive the control shaft 41. A lever 47 outside of the box 2, is keyed on the end of rock shaft 39 and is operated by a rod 48 which, at the finish of the winding operation, is actuated by the traversing thread-guide mechanism, not shown in the drawings. A pawl-arm 49 keyed to the rock shaft 39 within the box 2 engages (and is engaged by) a projection 50 on the dog 45 and while so engaged, keeps the dog 45 out of engagement with the catch-pins 42 of the gear 40, all as shown at Fig. 1. When the winding operation for one cop is finished, the rod 48 is moved forward by the thread-guide mechanism and causes the pawl 49 on the rock shaft 39 to release the dog 45 so that it hooks onto the next pin 42 arriving under it, and thereupon the spur gear 40, disc 43 and control counter-shaft 41 rotate as a unit for one complete revolution. In the meantime the pawl 49 will have been restored to its initial position by the return of the thread-guide rod 48 so that it is encountered by the projection 50 on the dog 45 and the latter is then automatically disengaged from the pin 42 and the control shaft comes to rest. Thus when the control shaft has once been started it must continue its motion until it has made one complete revolution. This arrangement is known as a single-cycling mechanism and will be herein referred to as such. The shaft 39 is the starter shaft.

Disc cams 51 and 52 are mounted fast on the control shaft 41 for actuating the mechanism for the bobbin change, cam 51 being for controlling the clutch 25, and cam 52 for reciprocating the bearing sleeve 36 of bobbin drive head 35 so as to release the full bobbin and engage the succeeding empty bobbin according to the understood cycle of these machines.

A control lever 93 mounted to rock on the shaft 39, has one arm 53 engaged to the cam 51 while the other arm has a head 54 loosely connected to a rod 59 (Fig. 2). The desired relationship between the lever 93 and rod 59 is maintained by nuts 56—57, yoke 55 and spring 58. The rod 59 is connected to a lever 60 which is pivoted at 61 in the box 2, said lever 60 having a pin 62 on which a roller 63 (Fig. 1) is rotatably mounted. This roller occupies the annular groove 64 of the compound worm-gear 26—27. A pull spring 72 anchored at 73 inside the box 2 and having its other end attached to the lever 93, pulls the cam-follower 53 against the cam 51.

Another control lever 94 also mounted to rock on the shaft 39 (see Fig. 3), has a cam follower arm 65 engaging the cam 52 and a head 66 on its other arm connected to a rod 70. The desired relationship between the lever 94 and rod 70 is maintained by the nuts 68—69 and the member 67. The rod 70 is connected to a post 71 on the sleeve 36. A pull spring 74 anchored at 73 inside the box 2, with its other end attached to the lever 94, pulls the cam follower 65 against the cam 52.

The top of the box 2 is entirely covered by a lid (not shown in the drawings) making the gear box dust-tight and capable of holding lubricant to be splashed on the gearing. It is pointed out that the parts which revolve at the high speed required for winding are disposed in the upper part of the casing where they can be above the level of any oil therein, and that the slower moving parts, such as the single-cycling mechanism

and thread guide cam, are in the lower part where they can splash oil onto the upper parts thereby affording adequate lubrication for indefinite periods without foaming the oil.

5 In starting up the winder the hand lever 14 is depressed and through the intermediary of the clutch fork 13, grooved ring 12, thrust bearings 10—11, pressure spring 8, the driving shaft 1 is shifted axially, pressing the friction disc 5 into

10 driving contact with the friction disc 6 on the power shaft 7, thus causing the driving shaft 1 to rotate. The hand lever 14 is held depressed by the locking device 19—20 (Fig. 5) under the control of the stop motion. If the thread breaks,

15 the stop 19 will be disengaged from the projection 20 of the member 21 so that the hand lever 14 is rocked by the spring 17 causing the clutch fork 13 to pull the friction wheel 5 away from its driving wheel 6.

20 In the automatic operation of the apparatus and at the point when the cop is full and ready to be replaced by an empty cop, the rod 48 is pulled forward (to the left in Fig. 1 by a part of the thread-guide system not shown), and this

25 rod by means of the lever 47 rocks the pawl 49 clear of the projection 50 of the dog 45 pivotally secured to the disc 43. Under the action of the spring 46 the dog 45 snaps inward and becomes engaged by one of the pins 42 on the constantly rotating gear 40 and thereby the control shaft 41 is set in motion. By the rotation of the control shaft 41 the cam 51 causes the compound worm-gear 26—27 to be shifted towards the left (Fig. 1) by the lever 93 and connecting rod 59,

30 thus separating the discs 25 and disconnecting the drive between the driving shaft 1 and the compound gear 26, 27, which gear is pushed so far to the left that the conical extension 75 at its end engages the conical recess 76 in the fixed bearing 3, which acts as a brake, with the result that rotation of the compound gear 26—27, thread guide traverse cam 29 and the driver head 35 is stopped. When the driver head 35 or winding-spindle comes to a standstill, it is retracted

35 (to the right in Fig. 3) by the rod 70, lever 94 and disc cam 52, thus allowing the cop 77 to drop by gravity into a chute not shown in the drawings. It will be understood that other cams are also mounted on the control shaft 41 to carry out

40 the other functions necessary for the automatic bobbin change but these are not shown in the drawings as they do not form part of the invention.

45 When the empty cop has been brought into place, the driver head 35 is pushed forward by cam 52 to clamp it, after which the worm-gear combination 26—27 is pulled back until the clutch 25 again drives the winding spindle and thread-guide drum cam 29. Thereupon the control shaft 41 will have made a complete revolution and the nose 50 of the dog 45 coming into contact with the pawl 49 disengages the dog 45 from the pin 42 on wheel 40 with the result that the rotation of the control shaft 41 is stopped.

50 It may be noted that the compound gear 26, 27, constitutes a coupling member which is intermittently operated to transmit the drive to the winding spindle and interrupt such drive and stop the spindle and further, that the starting of the spindle is without shock because the driving connection is made through a friction clutch (25) closed by the resilient pressure afforded by the spring (58) in the cam-operated connections, thereby shortening this part of the cycle.

55 Fig. 4 shows a safety device which can be used

for preventing breakage of any of the operating elements by excessive resistance in the event of the control shaft 41 being overloaded. Two collars 79 and 80 are fixed to the driving shaft 1, the collar 79 having a dog 78 which enters a slot cut in the forward end of the worm 18. The worm in this form is free on the shaft but is held in driving contact with the collar 79 by the spring 81. If the control shaft 41 is accidentally overloaded, the resistance of the wheel 37 will be so great that the reaction on the worm will overcome the pressure of the spring 81 so that the worm will be declutched from the collar 79. The control shaft 41 and the compound gear 26-27 will then come to a standstill until the overload on the control shaft is removed.

Fig. 5 shows another method of driving the power shaft 1 which consists of a motor 82 directly coupled to the shaft 1. With this method the driving shaft 1 is not axially shiftable in the box 2. The apparatus or unit is started and stopped by means of a switch 84, through which electric current is supplied to the motor 82, being actuated by a link mechanism 83 connected to the hand lever 14.

I claim:

1. In an automatic cop winder, a winding spindle, a high speed power shaft for driving said spindle, a coupling member between said spindle and shaft adapted to be reciprocated on said shaft while maintaining rotary driving connection with said spindle, a clutch between said coupling and power shaft adapted to be closed by the movement of the coupling in one direction and means driven by the power shaft for reciprocating said coupling member.

2. In an automatic cop winder, an endwise-moving bearing, a winding spindle therein, a power shaft, a coupling member on the power shaft having spur gear driving connection with said spindle and slidably movable with respect to said power shaft, and means driven by the power shaft for intermittently endwise moving said bearing and said coupling member.

3. In an automatic cop winder, the combination with a winding spindle, a power shaft, a coupling member on the power shaft movable endwise thereon and maintained in rotatory driving engagement with said spindle during such movement, a clutch between said coupling and the power shaft closed by movement of the coupling in one direction and a braking surface engaged by said coupling member when moved in the opposite direction, and means on the power shaft for intermittently moving endwise said member.

4. In an automatic cop winder, the combination with a winding spindle, a power shaft, a coupling member on the power shaft movable endwise thereon while in rotatory driving engagement with said spindle, a thread-guide actuating member driven by said coupling member, a clutch between said coupling member and the power shaft closed by movement of the coupling in one direction thereon and a braking surface engaged by said coupling member when moved in the opposite direction, and means on the power shaft for intermittently transmitting endwise movement to said member.

5. In an automatic cop winder, an enclosing casing, an endwise-moving bearing mounted in the wall thereof, a winding spindle in said bearing, a power shaft within the casing having a clutch-connection therein with said spindle, a counter-shaft in said casing and cam means on

5 said shaft for endwise moving said bearing and intermittently opening and closing said clutch connection.

6. An automatic cop winder comprising a machine frame in the form of a closed box or casing having mounted within it a single-cycling control mechanism, a power shaft, a winding spindle movable endwise in and through the casing wall for clamping and releasing cops, a clutch in said casing for connecting such spindle to and disconnecting it from driving relation to said power shaft, an operating connection from said mechanism to said spindle for endwise moving the latter for changing cops and another operating connection extending from said mechanism for operating said clutch.

7. An automatic cop winder comprising a machine frame in the form of a closed box or casing having mounted therein a single-cycling control cam shaft, a power shaft, a winding spindle movable endwise through the casing wall for clamping and releasing cops, a clutch for connecting such spindle to and disconnecting it from driving relation to said power shaft, and two cams on the said cam-shaft, one having an operating connection to said spindle for endwise moving it for changing cops and the other to said clutch for starting and stopping said spindle.

8. An automatic cop winder comprising a machine frame in the form of a box or casing having mounted therein a single-cycling control mechanism, a power shaft, a winder spindle, the latter being endwise movable through the casing wall for clamping and releasing cops, means in the casing for so moving said spindle, and means for stopping and starting said spindle in rotation comprising a friction clutch between the spindle and said power shaft and means operated by said control mechanism for applying resilient closing pressure to said clutch.

9. An automatic cop winder comprising a machine frame in the form of a box or casing having mounted therein a single-cycling control mechanism, a power shaft, a winder spindle adapted to be driven thereby, means for stopping and starting said spindle in rotation comprising a friction clutch between the spindle and said power shaft, means operated by said single-cycling mechanism for applying resilient closing pressure to said clutch and a spindle brake operated by the reverse movement of said last mentioned means.

10. An automatic cop winder comprising a machine frame in the form of a box or casing having mounted therein a cycling control, a power shaft and a winder spindle, the latter extended through the casing wall and endwise movable therein for clamping and releasing cops, means in the casing for so moving said spindle, a friction clutch through which such spindle is rotated by said power shaft, a spindle braking means and means for alternately opening said clutch and applying said braking means.

11. An automatic cop winder comprising a machine frame in the form of a closed box or casing having mounted therein a single-cycling control mechanism including a shaft extending to the outside of the casing for calling said mechanism into action, a power shaft journaled in the casing; a winding spindle, movable endwise through a wall of the casing for clamping and releasing cops, a clutch for connecting the inner end of such spindle to and disconnecting it from driving relation to said power shaft, an operating connection from said mechanism to said spindle for

endwise moving it for changing cops, another connection therefrom for operating said clutch, and a thread-guide rod outside said casing operatively connected to said shaft of the single-cycle mechanism.

12. An automatic cop winder comprising a machine frame in the form of a box or casing having mounted therein a single-cycling control mechanism including a shaft extending outside the casing for calling said mechanism into action, a power shaft and a winder spindle, both journalled in the wall of the casing, the latter being endwise movable through the casing wall for clamping and releasing cops, means in the casing for so moving said spindle, and means for stopping and starting said spindle in rotation comprising a friction disc clutch between the spindle and said power shaft and means operated by said mechanism for applying resilient closing pressure to said clutch, a spindle brake operated by said last mentioned means, and a thread-guide rod outside the casing operatively connected to said shaft of said single-cycle mechanism.

13. In an automatic cop winder, a casing suitable for holding a body of oil, a winding spindle extending through the wall of such casing with its winding head on the end thereof outside the casing and its other end located within the casing, a power shaft rotating at substantially winding speed journalled within said casing at substantially the same level as said spindle and including a clutch associated with said power shaft adapted for connecting it to and disconnecting it from the spindle, all said parts being located in the upper part of said casing, in combination with a single-cycling controlling cam, connections therefrom for operating said clutch and reduction drive-gearing between said power shaft and said cam, said cam being journalled in the lower part of said casing, whereby the oil in said casing may cover the slow-moving parts and the higher-speed parts receive their oil only from the latter members.

14. In an automatic cop winder, a casing adapted to hold a body of lubricating oil, a winding spindle mounted for endwise movement through the upper part of the wall of said casing for clamping and releasing cops, a power shaft rotated at substantially winding speed also journalled in the upper part of said casing at substantially the same level as said winding spindle, a clutch associated with said power shaft for connecting and disconnecting it with said spindle, in combination with reduction gearing driven by said power shaft, a thread-guide actuator cam and a single-cycling cam driven by said gearing, said latter cam having connections for endwise moving said spindle and both cams being mounted below said shaft and spindle in the lower part of said casing whereby the oil in said casing may cover said slow-moving cam members and the high-speed members receive their oil from the latter, and a thread-guide rod outside said casing having a connection with said single-cycling means within said casing.

15. In an automatic cop winder, a casing suitable for holding a body of oil, a winding spindle journalled in the upper part of such casing so that it can be above the oil therein and extending through the wall of such casing with its winding head outside the casing and its other end within the casing, said winding head being endwise movable for clamping and releasing cops, a power shaft rotating at substantially winding

speed and also journalled in the upper part of said casing, a clutch associated with said power shaft for connecting it to and disconnecting it from the spindle and a thread-guide cam-shaft driven by said clutch, in combination with single-cycling mechanism including a cam and operating connections for operating said winding head and clutch, said mechanism being journalled in the lower part of said casing where it can be submerged in oil and being driven by reduction gearing from said power shaft, and a thread-guide rod having a connection through the wall of said casing for controlling said single-cycling mechanism.

16. In an automatic cop winder, the combination with a winding spindle having a winding head which is endwise movable to clamp and release cops, an associated power shaft having an endwise-movable coupling member driven thereby and in rotary driving connection with said endwise-movable head, a clutch adapted to be closed by the endwise movement of said member and a single-cycling mechanism driven through reduction-drive gearing by said power shaft and including cams and cam-operated connections therefrom to said spindle and coupling member respectively and organized for successively endwise shifting each of them.

17. In an automatic cop winder, the combination with a winding spindle having a winding head movable endwise to clamp and release cops, a thread-guide cam-shaft, an associated power shaft, an endwise-movable coupling member thereon, said member being in constant rotatory driving connection with said head and cam shaft, a clutch adapted to be closed by the endwise movement of said member to transmit the rotation of the power shaft thereto, a single-cycling mechanism, reduction-drive gearing therefor connecting the same with said power shaft, said mechanism including cams and operating connections therefrom respectively to said spindle and coupling member and adapted for successively endwise shifting them.

18. In an automatic cop winder, the combination with a winding spindle having a winding head movable endwise to clamp and release cops, a thread-guide cam-shaft, an associated power shaft having thereon a compound gear coupling member including a gear for driving said spindle and a worm for driving said cam-shaft, a clutch for connecting said coupling member to the power shaft, a single-cycling mechanism, reduction-drive gearing between said power shaft and mechanism, and cams included in said mechanism having operating connections therefrom to said head and clutch respectively adapted for successively operating them.

19. In an automatic cop winder, a power shaft rotating at substantially winding speed, a worm fixed on said shaft, a single-cycling mechanism driven thereby, a coupling member on said shaft including a worm and a thread-guide cam-shaft driven by said worm, in combination with a clutch between said second worm and the power shaft and a cam included in said mechanism with operating connections to said clutch.

20. In an automatic cop winder, a power shaft journalled in the upper part of a casing adapted to contain oil, a worm fixed on said shaft and a single-cycling mechanism driven by said worm and mounted in the lower part of said casing, a compound gear on said shaft including a worm and a spur gear, a thread-guide cam-shaft driven

by said latter worm, a winding spindle driven by said gear, a clutch between said second worm and said power shaft and an operating connection between said mechanism and said clutch.

21. An automatic cop winder comprising a machine frame in the form of a closed box or casing having mounted within it a single-cycling control mechanism, a power shaft and a winding spindle, a winding head driven by said spindle outside the casing and endwise movable for clamping and releasing cops, a clutch in said casing for connecting such spindle and its head to and disconnecting them from driving relation to said power shaft, an operating connection from said single-cycling mechanism to said winding head for endwise moving the latter for changing cops and another operating mechanism extending from said single-cycling mechanism for operating said clutch. 10 15

22. An automatic cop winder comprising a machine frame in the form of a closed box or casing having mounted within it a single-cycling control mechanism, a power shaft and a winding spindle, a winding head driven by said spindle outside the casing and endwise movable for clamping and releasing cops, a clutch in said casing for connecting such spindle and its head to and disconnecting them from driving relation to said power shaft, an operating connection from said single-cycling mechanism to said winding head for endwise moving the latter for changing cops, another operating mechanism extending from said single-cycling mechanism for operating said clutch, and a brake for the winder head operated by the last mentioned connection.

WALTER SCHWEITER.
